(57) **CLAIM**

The ornamental design for a calibration board for head up display of vehicle, as shown and described.

DESCRIPTION

FIG. 1 is a top, rear and left side perspective view of a calibration board for head up display of vehicle showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and

FIG. 7 is a bottom plan view thereof; and,

FIG. 8 is an enlarged view of a circled part of FIG. 4.

The broken lines in the drawings illustrate portions of the calibration board for head up display of vehicle which form no part of the claimed design.
